EXTENSIBLE CLAMP

Clarence C. Lang, Los Gatos, Calif.

Application March 15, 1952, Serial No. 276,734

3 Claims. (Cl. 144—299)

1

The present invention relates to clamps, and pertains more particularly to an extensible bar clamp.

In woodworking, such as cabinet and pattern making, it frequently is necessary to glue a plurality of boards together. For such work it is customary practice to employ one or more clamps each having an elongated body portion, a fixed or adjustable jaw on one end of the body portion, and a screw-actuated clamp member on the other end of the body portion.

The present invention contemplates the provision of an improved extensible bar clamp. The invention also provides for a bar clamp having a wide range of adjustment so that the number of styles of clamps required will be minimized. The invention also has for an object the provision of a clamp which can be shortened to occupy a small space for shipping or storing, but which can be elongated by a series of increments to span a work piece of substantial dimension.

These and other objects and advantages of the invention will be apparent from the following description and the accompanying drawings, comprising one sheet, wherein:

Fig. 1 is a side elevational view of an extensible bar clamp embodying the present invention, intermediate a body portion, and an adjustable jaw member being broken away.

Fig. 2 is an edge elevational view of the clamp shown in Fig. 1.

Fig. 3 is a transverse sectional view taken along line 3—3 of Fig. 1.

Fig. 4 is a transverse sectional view taken along line 4—4 of Fig. 1.

Fig. 5 is a transverse sectional view taken along line 5—5 of Fig. 1.

Fig. 6 is a transverse sectional view taken along line 6—6 of Fig. 2.

Fig. 7 is a fragmentary longitudinal sectional view taken along line 7—7 of Fig. 1.

In the illustrated form of the invention, a bar clamp A, has an elongated body assembly B, an adjustable jaw member C, and a clamping screw D.

The elongated body assembly B comprises a first or outer steel channel portion 10 with a stop plate 11 secured by screws 12, 12 across an end thereof. The ends of the stop plate 11 project beyond the sides of the channel member 10 to limit the outward movement of the adjustable jaw member C which is mounted for slidable adjustment on the channel member 10.

While the stop plate 11 and several of the other parts of the present clamp A are shown as being

2

joined by screws, it is obvious that most if not all of these connections may be made by welding or silver soldering if desired.

The jaw C comprises a metal block 13 having a recess 14 therein to receive the channel member 10 freely therein. A plate 15 is secured to a side of the block 13 to extend across the recess 14 to retain the channel member 10 therein (Figs. 1 and 2). Sufficient clearance space 13a may be provided between the channel member 10 and the jaw member C to permit the jaw member to be moved slidably over a keeper band to be described later herein.

A jaw anchoring pin 17 is slidably mounted in a hole 18 provided therefor in the jaw block 13, the inner end of the pin 17 being of a size to enter any of a plurality of anchor holes 19 provided along one side flange of the channel member 10. A coil spring 20, held in compression between an offset shoulder 21 in the hole 19 and a flange 22 surrounding the pin 17 urges the pin axially inwardly to move the inner end of the pin 17 into any of the holes 19 with which it is brought into register. A knob 23, screwed onto the threaded outer end of the pin 17, provides a grip for manually retracting the pin, and also (Fig. 1) acts as a stop to limit the inward movement of the pin 17 under the impulse of the spring 20.

A U-bracket 24 is formed to fit onto the opposite end of the channel member 10 from the stop plate 11 to extend across the channel therein, and is secured thereto by screws 25. A latch lever 27 is pivoted on a pin 28 extending transversely between a pair of ears 29, 29 (Figs. 2, 6 and 7) mounted on the bracket 24.

A latch pin 30 is mounted in one end of the latch lever 27 and extends inwardly so as to enter any of a plurality of holes 31 (Figs. 1 and 7) provided in an inner channel member 32 with which it is brought into register. A notch 33 in the bracket 24 is of a size to permit the latch pin 30 to move freely upon pivotally moving the latch lever 27. A coil spring 34 is held in compression between the bracket 24 and the latch lever 27. The spring 34 is retained against dis-

placement by a pin 35 mounted on the bracket 24 and inserted in the inner end of the spring 34. A recess 37 in the lever 27 receives the outer end of the spring 34.

The second or inner channel member 32 is inserted for slidable movement in relatively reversed position in the first or outer channel member 10 so as to move slidably therein within the bracket 24. Sufficient clearance space 38 (Fig. 4) is provided between the outer sides and

3

edges of the inner channel member 32 and the outer channel member 10 to receive a bar keeper band to be described later herein.

A keeper band 39 is provided around the first or outer channel member 10 to have a sliding fit thereon, and is secured by screws 40 to the left hand end (as illustrated in Figs. 1 and 2) of the inner channel member 32. This keeper band 39 retains within the first channel member 10 the left hand end of the inner channel member 32 in any slidably adjusted position of the inner channel member 32.

A U-shaped bracket 41 is mounted on the projecting or right hand end of the inner channel member 32 to extend across the open side of the channel therein, and is secured to the channel member 32 by screws 42. A latch lever 43, similar to the latch lever 27 is mounted on the bracket 41 to engage any of a plurality of holes 44 (Figs. 1 and 2) provided in a rectangular bar member 45.

The bar member 45 is inserted for slidable adjustment in the inner channel member 32. The U-bracket 41 retains the outer or right hand portion of the bar member 45 within the inner channel member 32. A keeper band 47 (Figs. 1, 2 and 5) encircles the inner channel member 32 and is secured by screws 48 to the left hand end (as illustrated in Figs. 1 and 2) of the bar member 45. The keeper band 47 is of a thickness to fit slidably within the clearance space 38 provided between the outer and inner channel members 10 and 32.

The projecting or right hand end portion 49 (Figs. 1 and 2) of the bar member 45 is bent to extend laterally from the remainder of the bar member 45, and a usual pressure or clamp screw 50 is threadedly mounted in a boss 51 on the outer end of the lateral projection 49.

The manner of using the invention will be apparent to anyone familiar with bar clamps. For example, the adjustable jaw C may be moved slidably along the outer channel member 10 upon withdrawing the anchor pin 17 clear of the outer channel member 10.

Sufficient clearance space 13a (Figs. 1 and 2) is provided between the walls of the recess 14 and the outer channel member 10 if desired to allow the jaw member C to be moved slidably over the keeper 39. When so arranged, the keeper 39 preferably should be of thin material in order to minimize the amount of clearance space 13a required. Since this keeper 39 is not subjected to severe stresses in using the device it is not necessary that it be very strong.

The inner channel member 32 may be extended or retracted as desired upon tilting the latch lever 27 to withdraw the latch pin 30 from any of the openings 31 in which it may be inserted. Upon releasing the latch lever 27 and relatively moving the inner channel member 32 to bring the latch pin 30 into register with one of the openings 31 in the side flange 32a, the spring 34 will tilt the lever 27 in a counter-clockwise direction to the position shown in Figs. 2 and 7 to again latch the two channel members 10 and 32 together. The relatively extended or retracted position of the bar member 45 also can be adjusted in a similar manner by manipulating the latch lever 43.

While I have illustrated a preferred embodiment of my improved bar clamp it will be understood by those familiar with the art that various changes and modifications may be made in the details thereof without departing from the spirit

4

and scope of the invention as set forth in the appended claims.

Having thus described my invention, what I claim as new and desire to protect by Letters Patent is defined in the following claims.

I claim:

1. An extensible clamp comprising a first relatively wide and shallow channel member having a plurality of anchor elements disposed lengthwise thereof, a jaw member slidably mounted on said first channel member to extend laterally therefrom, means on said jaw member for interlockingly engaging selected anchor elements on said first channel member, a second channel member of a size and shape to fit closely within the first channel member mounted in reversed position within said first channel member for slidable movement lengthwise therein, means for securing the two channel members in relatively adjusted position, an inner member of a size and shape to fit closely within the second channel member inserted in the second channel member for slidable movement lengthwise therein, means for securing the inner member in longitudinally adjusted position within said second channel member a laterally extending screw mounting element mounted on said inner member longitudinally opposite said jaw, and a clamping screw threadedly engaging said screw mounting element to exert pressure on a work piece interposed between said clamping screw and said jaw.

2. An extensible clamp comprising a relatively wide and shallow first channel member having a plurality of anchor elements disposed lengthwise thereof, a jaw member slidably mounted on said first channel member to extend laterally therefrom, means on said jaw member for interlockingly engaging selected anchor elements on said first channel member, a second channel member of a size and shape to fit closely within the first channel member mounted in reversed position within said first channel member for slidable movement lengthwise therein, a support mounted on said first channel member in position to retain the second channel member therein, a spring biased latch on said support for securing the two channel members in relatively adjusted position, a bar member slidably inserted in the second channel member for slidable movement lengthwise therein, a support on said second channel member in position to retain the bar member therein, a spring biased latch on said latter support for securing the bar member and second channel members in relatively adjusted position, a laterally extending element mounted on said bar member longitudinally opposite said jaw, and screw means having operative connection with said laterally extending element to exert pressure on a work piece interposed between said laterally extending element and said jaw.

3. An extensible clamp comprising a first relatively wide and shallow channel member having a plurality of anchor elements disposed lengthwise thereof, a jaw member slidably mounted on said first channel member to extend laterally therefrom, means on said jaw member for interlockingly engaging selected anchor elements on said first channel member, a second channel member of a size and shape to fit closely within the first channel member mounted in reversed position within said first channel member for slidable movement lengthwise therein, a keeper band mounted slidably to encircle the first channel member and secured to the second channel member adjacent an end thereof, a support

mounted on said first channel member in position to retain the second channel member therein, a spring biased latch on said support for securing the two channel members in relatively adjusted position, a bar member of a size and shape to fit closely within the second channel member slidably inserted in the second channel member for slidable movement lengthwise therein, a keeper band mounted slidably to encircle the second channel member and secured to the bar member, a support on said second channel member in position to retain the bar member therein, a spring biased latch on said latter support for securing the bar member and second channel members in relatively adjusted position, a laterally extending element on said bar member longitudinally opposite said jaw, and screw means hav-

ing operative connection with said offset element to exert pressure on a work piece interposed between said offset element and said jaw.
